UNITED STATES PATENT OFFICE.

MARIANO DE' SPERATI, OF TURIN, ITALY, ASSIGNOR TO ARGENTOGRAPHICA (U. S. A.) LIMITED, OF LONDON, ENGLAND.

FILM FOR PHOTOCOLLOGRAPHIC PRINTING PLATES.

Original application filed June 4, 1923, Serial No. 643,435, and in Italy May 12, 1923. Divided and this application filed November 28, 1925. Serial No. 72,012.

This invention relates to the preparation of photocollographic printing plates having complementary pressure-equalizing relief portions on their backs of the kind described in my copending application Ser. No. 643-435, filed June 4, 1923, now Patent No. 1,587,220, granted June 1, 1926, of which the present case is a division, and has for its object the provision of a film adapted for use in said preparation.

According to the present invention the film comprises a transparent or translucent support, say of celluloid, and two gelatine layers, each on one of the support faces, the one of said layers which is on the side of the support on which the printing surface of the final printing plate is to be obtained being of such a character as to be less easily dissolved than the other layer which is intended to provide the pressure equalizing relief.

Said two layers are of gelatin and one of them is of a gelatin adapted to dissolve say at a temperature of 50° C. while the other one is of a gelatin adapted to dissolve at a somewhat lower temperature, say at 40° C.

The single figure of the annexed drawing is a transverse section on an enlarged scale of a film according to the present invention.

In said figure, 1 is a transparent or translucent support, say of celluloid, and 2 and 3 are the two gelatin layers above referred to, the layer 2 being of a gelatin adapted to dissolve at a higher temperature than the gelatin of layer 3.

For use, said two layer film is sensitized by means of an alkali bichromate bath and dried, and then is exposed to light under a negative image, with its less-easily dissolved layer in contact with the negative.

After exposure to light the gelatin of both layers is left in water-absorbing con-

dition in register with the dark portions of the negative while it is made insoluble in both layers in register with the transparent portions of the negative. 45

Said film is then treated with water at a temperature of 40° C., say by dipping it in a bath of water having such a temperature. Such treatment does not affect the layer of gelatin dissolving at 50° C. and it merely removes from said layer the alkali bichromate not acted on by light, while in the other gelatin layer it removes gelatin to a more or less full extent in places where it has not been made insoluble by the action of light on alkali bichromate—that is, in register with dark portions of the negative, while gelatin is left unaffected in places where it has been acted on by light and made hard—that is, in register with transparent portions of said negative. 55 60

By the described treatment the film has on its back side relief portions in register with the hard and ink-retaining portions of its printing layer, while it shows on said back side depressions in register with swelled out portions of said printing layer. 65

Reference is made to my previously mentioned copending application Ser. No. 643-435, in respect of features not claimed in the present application. 70

What I claim as my invention and desire to secure by United States Letters Patent is:—

A film for use in making photocollographic printing plates having a layer of gelatin on each face thereof, one of said layers being made of gelatin which is adapted to dissolve at a lower temperature than the 80 gelatin providing the other one of said layers. 75

In testimony whereof I affix my signature.
MARIANO DE' SPERATI.
